UNITED STATES PATENT OFFICE.

THEODORE FLETCHER, OF SAN ANTONIO, TEXAS, ASSIGNOR OF ONE-HALF TO J. M. NIX, OF BEXAR COUNTY, TEXAS.

SPEED-REGULATING MEANS.

Application filed June 20, 1918. Serial No. 240,995.

To all whom it may concern:

Be it known that I, THEODORE FLETCHER, a subject of the King of Great Britain, and a resident of San Antonio, in the county of Bexar and State of Texas, have invented certain new and useful Improvements in Speed-Regulating Means, of which the following is a specification.

My invention relates to improvements in speed regulating means for phonographs, it being more particularly an improvement on the subject matter of my former application filed May 16, 1917, Serial No. 168,972, and it consists in the constructions, combinations and arrangements herein described and claimed.

An object of my invention is to provide a phonograph wherein a differential rotational speed is imparted to the turn table so that an equal speed of disk travel under the recorder or reproducer is maintained throughout the recording or playing of a record.

Another object of the invention is to provide means whereby a positive lateral movement for the turn table driving friction wheel is obtained from the turn table spindle.

Another object of the invention is to provide means for conveying the reproducer across the disk to avoid the friction between the stylus and the sound groove of the record, said means being operated positively from the same source which provides the positive lateral movement of the friction wheel.

A further object of the invention is to provide a phonograph embodying means for driving the turn table either at a differential speed or at a uniform speed, according to the type of record it is desired to play.

A further object of the invention is to provide means whereby the friction wheel may be made to traverse the turn table either rapidly or slowly according to the type of record it is desired to play.

A further object of the invention is to provide means whereby the contact of the friction wheel with the turn table and the engagement of the lateral driving means for the friction wheel carriage, is simultaneously broken to enable the return of the friction wheel to the original or starting position.

Other objects and advantages will appear in the following specification, reference being had to the accompanying drawings in which:

Figure 1 is a plan view of the improved speed regulating means,

Figure 2 is a detail sectional view on the line 2—2 of Figure 1, showing the notched handle whereby the adjustments of the friction wheel supporting yoke are obtained,

Figure 3 is a cross section on the line 3—3 of Figure 1,

Figure 4 is a detail cross section on the line 4—4 of Figure 1,

Figure 5 is an enlarged section of a portion of the mechanism illustrated in Figure 3, and

Figure 6 is a detail view of an improved automatic stop.

As previously stated, the present invention is an improvement on the subject matter of my prior application, and in order that the differences in construction and the mode of operation may more readily be understood, it is thought best to outline

A synopsis of the description of the original structure.

In this structure, a disk-holding turn table was revolved by means of a positive gear connection with a motor. This motor was subject to variable speeds. A friction wheel arranged to traverse the turn table by means of a connection with a screw shaft, was in contact with the bottom surface of the turn table. The screw shaft was driven from one of the gear connections of the turn table spindle. The shaft which supported the friction wheel and upon which the friction wheel was slidably, was geared to a governor. The governor included a brake and a brake disk. In starting and when the friction wheel was at the periphery of the turn table, the rotational speed of the friction wheel was relatively great so that the governor balls flew outwardly and the brake came into action thus tending to retard the speed of the turn table.

As the friction wheel approached the center of the turn table, the rotational speed of the friction wheel was not so great, conse-

quently the governor balls partly collapsed, releasing the brake and causing the rotation of the turn table to speed up in accordance. The arrangement was such that the reproducer was positively moved across the record and in alignment with the friction wheel beneath, and the result of this arrangement was that the speed of the record beneath the reproducer needle was always the same 10 whether the reproducer needle was at the periphery of the disk or near the center.

The mode of operation of the present invention is reversed in some respects although the ultimate result, namely, of gradually increasing the speed of rotation of the turn table as the reproducer nears the center of the record, is obtained. Therefore, proceeding with the description, the present invention consists of a friction wheel 15 which is in contact with the bottom surface of the turn table 2 and is arranged to drive the turn table by means of the frictional contact of a rubber tire 3 with said bottom surface. A motor M is arranged to 20 rotate the friction wheel 1 in the preferred form of the invention. The motor M is intended to be one of a constant speed, to which end, any suitable governing device may be employed, although the illustration 25 of such is omitted from the drawings.

The driving connection between the motor M and the friction wheel 1 consists of a motor shaft upon which a pinion 4 is mounted. The pinion 4 meshes with a similar pinion on a primary shaft 5 from which a secondary or pivot shaft 6 is driven by means of the bevel gear connections 7. The shafts 5 and 6 are at right angles to each other and the shaft 6 carries a spur 30 pinion 8 which meshes with a spur gear 9 on the friction wheel drive shaft 10. The shaft 10 drives the friction wheel 1 and consequently the turn table 2 is rotated. The friction wheel 1 is made to traverse the 35 turn table 2 by means of

The friction wheel carriage 11.

The carriage 11 slides on a guide rod 12 which is fixed in position in standards 50 13 which in turn rise from a bed plate 14. A screw follower 15 carried by the carriage 11, engages the threads of a driving screw 16. The motion of the driving screw causes the friction wheel carriage 11 to move inwardly with respect to the turn table, and the friction wheel 1 accordingly traverses the turn table by virtue of the connection of a yoke 17 on the carriage with a grooved hub 18 on the friction wheel.

60 The turn table 2 is the source from which the driving screw 16 is rotated. The turn table spindle 19 carries a bevel pinion 20 which drives a gear connection 21. This gear connection is partly supported in the bearing standard 22 of the spindle 19, and

drives a bevel gear 23 on a counter shaft 24. The counter shaft has large and small gears 25 and 26 with which corresponding gears 27 and 28 on a screw extension shaft 29 are adapted to mesh.

70 Two speeds of the screw 16 are obtained through the medium of the gear connections just described. These two speeds are necessary to accomplish either a slow or rapid traversing of the friction wheel 1 75 across the turn table to accommodate the differences in the grooves in various types of records. A speed lever 30 secures the shifting of the gears 27 and 28 so that either the gears 25 or 26 on the counter shaft 24 80 may be engaged. The screw 16 may be rendered operative or inoperative at will, according to the position of a clutch 31 which is actuated by a clutch lever 32.

85 The friction wheel tension adjustment includes a yoke 33 in which the drive shaft 10 of the friction wheel 1 is journaled. It should be observed that the drive shaft 10 has a groove with a suitable key or spline, in which the hub of the friction wheel rides 90 thus securing the rotational movement of the friction wheel yet enabling the longitudinal movement thereof on the drive shaft. The arms of the yoke 33 are pivoted on the pivot shaft 6 so that the yoke 33 may 95 be rocked on the pivot shaft to move the friction wheel 1 into and out of contact with the bottom surface of the turn table.

100 Projecting forwardly from the yoke 33 is a spring 34. This spring is in the nature of a tongue upon which a vertically disposed handle 35 is mounted. The handle 35 has a plurality of notches 36 which are arranged to engage a keeper 37 of any suitable design. By pressing down on the handle 105 35, the yoke 33 is made to rock on the pivot shaft 6 and the rubber tire 3 of the friction wheel 1 is made to press against the turn table 2 to a degree according to the distance of depression of the handle 35. Upon pulling the handle 35 farther out than shown in Figure 2, the friction wheel 1 may be made to leave the turn table so as to secure the freedom of movement of the friction wheel as when returning it to the original 110 position.

115 Simultaneously with the pressing into engagement of the friction wheel 1 with the bottom surface of the turn table 2, the screw follower 15 is made to engage the screw 16. This is accomplished through the correlation of the hub of the friction wheel 1 with the friction wheel carriage 11. It will be readily understood that on pressing the friction wheel 1 upwardly against 120 the turn table, the screw follower 15 will be correspondingly pressed downwardly so as to secure the interengagement of the parts in the manner just described.

125 Conversely when the friction wheel 1 is 130

moved downwardly and out of contact with the turn table 2, the screw follower 15 is lifted clear of the screw 16. A lever 38 pivoted at 39 has a swiveled engagement 40 with a depending portion of the friction wheel carriage 11. This lever includes a handle 41 by means of which the carriage 11 is returned to the starting position when the screw follower 15 is lifted as just described.

The tone arm carriage 42 slides on guides 43 which are fixed in position on suitable supports in the phonograph cabinet C. The carriage 42 traverses the phonograph cabinet C at the same speed of lateral motion as that of the friction wheel 1. The reproducer R is thus positively conveyed across the record and not dragged across by virtue of the engagement of the needle with the grooves as is ordinarily the case.

A screw 44 driven by the gear connections 45 from the continuation 29 of the screw 16, conveys the carriage 42 across the cabinet as just described, by means of the engagement of a screw follower 46 with the screw 44. The follower 46 is mounted on a spring extension 47 on a plate 48 which is hinged on the carriage 42. The screw follower 46 is returned to the starting position on the screw 44 by simply lifting the tone arm T at which time the plate 48 rocks on its hinges.

A telescopic arrangement is provided in the various members of the tone arm and the sound amplifier or horn S. This arrangement is well shown in Figure 3 wherein the telescopic members of the tone arm T are illustrated. A tube 49 is fixed in any suitable manner on the hinge plate 48, and the lower end of this tube projects into the upper elbow 50 of the sound conduit which leads to the horn S. The upper end of the elbow 50 is likewise fixed in the carriage 42 but the connection between the tube 49 and the elbow 50 is loose enough to enable the disengagement of the screw follower 46 from the screw 44 when the plate 48 is lifted on its hinges in the manner just described. Suitable swivel joints are provided in the sound conduit so that the movement of the carriage 42 may be followed very readily and effectively.

An alternate method of driving the turn table 2 includes a counter shaft upon which a shiftable pinion 51 as illustrated in Figure 1, is mounted. The pinion 51 is arranged to be shifted into engagement with a gear 52 on the spindle 19 by means of a pivoted lever 53. The shaft upon which the pinion 51 is mounted, is driven by means of the gear connections 54 from the gear 55 on the primary shaft 5. When the pinion 51 is thrown into driving engagement with the gear 52, the turn table 2 is driven at a uniform rate of speed and the speed is not ac-

celerated as is the case when the turn table is driven by the friction wheel 1. When the turn table 2 is thus driven, the friction wheel 1 is thrown down out of engagement with the turn table. The tone arm carriage 42 is, however, positively conveyed across as in the former instance.

A supporting wheel 56 is mounted in suitable bearings on the opposite side of the spindle 19. This supporting wheel is similar in construction to the friction wheel 1 and its purpose is to sustain the turn table 2 on the other side and thus compensate for the pressure of the friction wheel on the right side of the turn table. By this provision, lateral strains on the spindle 19 and its bearing, are avoided. In this connection it should be observed that the spindle 19 is mounted in ball bearings in the bearing standard 22 as clearly shown in Figure 4. The lower ball bearing cup is adjustable so that the spindle 19 may be moved to a true perpendicular position should such adjustment be required.

An automatic stop cooperates with the tone arm carriage 42 so as to stop the playing of the record at any desired place. This stop is illustrated in Figure 6 and it consists of a rod 57 which has a stop 58. The stop 58 is adapted to be engaged by a finger 59 on a portion of the tone arm T and preferably extending forwardly from the tube 49.

A trip lever 60 has a projection which rests on an arm extending from one of the supports of the rod 57, and when the finger 59 has moved over far enough to engage the stop 58, further movement of the finger 59 will cause the displacement of the trip lever 60 which then moves downwardly under the influence of the spring 61. This downward movement of the trip lever 60 is utilized to either apply a brake or break an electric motor circuit according to the type of motor M used in the phonograph.

The rod 57 moves over in the direction just described against the tension of a spring 62 at one end, and when the finger 59 releases the stop 58, the rod 57 springs back to its original position. The trip lever 60 has a finger piece by means of which it may be reset. The stop 58 is made adjustable on the stop 57 so that the operation of stopping the motor may be carried out at any desired time.

The operation.

The reproducer R is conveyed across the record by a positive motion which is derived from the turn table itself. The turn table 2 is capable of being rotated either at a variable speed or at a constant speed from the constant speed motor M.

In the former instance, the friction wheel 1 is made use of. This wheel is arranged

to traverse the turn table 2 and at the same time, causes the rotation of the turn table by means of the frictional contact of the rubber tire 3 with the bottom surface of 5 the turn table.

The motor M drives the friction wheel 1 through the primary shaft 5, the secondary or pivot shaft 6, the intermeshing gears 8 and 9, and the spline and groove connections of the drive shaft 10 upon which the friction wheel is mounted. When the friction wheel 1 is positioned at the periphery of the turn table 2, the rotational speed of the turn table will be relatively slow. As 10 the friction wheel 1 approaches the center of the turn table, the rotational speed of the turn table will become gradually accelerated. The reproducer R which is arranged to follow the friction wheel 1 will 15 thus reproduce sound from the record which is made to move at the same rate of speed beneath the reproducer needle at all positions of the reproducer. This rate of speed has been determined in actual practice to 20 be about 18" per second and this rate of speed secures the best reproducing results.

Two speeds of transverse movement of the friction wheel carriage 11 which conveys the friction wheel 1, are obtained by 25 means of the gears 25, 26, 27 and 28. These are actuated by the lever 30. The tone arm carriage 42 is positively conveyed across under all circumstances.

Should it be desired to have the turn 30 table 2 revolve at a uniform rate of speed as when playing ordinary records, the friction wheel 1 is lowered by means of the yoke 33 and the handle 35, and the pinion 35 51 is shifted into engagement with the gear 52 on the spindle 19 so that motion is derived directly from the primary shaft 5. Under such circumstances, the clutch 31 is shifted out of engagement with the corresponding clutch element on the end of the 40 screw 16, and thus the screw 16 remains quiet. Obviously the process of reproducing a record which starts from the center instead of at the periphery, may be carried out by simply making the screws 16 and 45 44 with left hand threads. It is also conceivable that the screw shaft 44 and the driving gear connections therefor may be eliminated; the transverse conveyance of the tone arm carriage 42 being then accomplished by simply extending the screw follower 46 into engagement with the screw 16.

While the construction and arrangement 50 of the device as herein described and illustrated is that of a generally preferred form, obviously modifications and changes may be made without departing from the spirit of the invention or the scope of the claims.

I claim:

1. In a phonograph, a turn table, a fric-

tion wheel in driving contact with the turn 65 table, a friction wheel shaft, a shaft supporting yoke, a driven shaft providing a pivotal mounting for the yoke, driving means between said shaft and the friction wheel shaft, a resilient member carried by 70 the yoke, a notched handle on said resilient member adapted to enable the rocking of the yoke on its pivotal mounting to secure the engagement or disengagement of the friction wheel with the turn table, and 75 fixed engaging means cooperating with the notches of said handle.

2. A phonograph including a turn table and spindle, a friction wheel for rotating the turn table, a friction wheel carriage 80 including connecting means to the friction wheel, supporting means for the carriage, a counter shaft, gear connections for driving the counter shaft from the turn table spindle, gears of different diameters on the 85 counter shaft, a carriage actuating screw shaft, a separate screw extension shaft, shiftable gears of two diameters on said extension adapted to engage corresponding ones of the gears on the counter shaft and 90 impart various rotational speeds to the extension shaft, shifting means for said extension shaft carried gears, clutch connections between the screw shaft and the extension shaft, shifting means for said clutch connection, and a screw follower carried by the friction wheel carriage in engagement with the screw shaft for conveying the carriage and the friction wheel toward the center of the turn table.

3. A phonograph including a turn table and spindle, a friction wheel for rotating the turn table, a friction wheel carriage including connecting means to the friction wheel, supporting means for the carriage, 105 a counter shaft, gear connections for driving the counter shaft from the turn table spindle, gears of different diameters on the counter shaft, a carriage actuating screw shaft, a separate screw extension shaft, 110 shiftable gears of two diameters on said extension adapted to engage corresponding ones of the gears on the counter shaft and impart various rotational speeds to the extension shaft, shifting means for said extension 115 shaft carried gears, clutch connections between the screw shaft and the extension shaft, shifting means for said clutch connection, a screw follower carried by the friction wheel carriage in engagement with 120 the screw shaft for conveying the carriage and the friction wheel toward the center of the turn table, and movable means enabling the simultaneous disengagement of the friction wheel from the turntable and screw 125 follower from the shaft.

4. A phonograph including a turn table and spindle, a friction wheel for rotat-

- ing the turn table, a friction wheel carriage including connecting means to the friction wheel, supporting means for the carriage, a counter shaft, gear connections for driving the counter shaft from the turn table 5 spindle, gears of different diameters on the counter shaft, a carriage actuating screw shaft, a separate screw extension shaft, shiftable gears of two diameters on said extension shaft carried gears, clutch connections 10 between the screw shaft and the extension shaft, shifting means for said clutch connection, a screw follower carried by the friction wheel carriage in engagement with the screw shaft for conveying the carriage 15 and the friction wheel toward the center of the turn table, movable means enabling the simultaneous disengagement of the friction wheel from the turn table and the screw follower from the screw shaft, and means 20 in connection with said friction wheel carriage for returning the carriage and the friction wheel to the original position.
5. The combination of a pair of screw shafts, an extension shaft of one of the screw 30 shafts, a turn table, a friction wheel in driving contact with the turn table, a friction wheel drive shaft arranged to be driven at a uniform rate of speed, spline and groove connections between the friction wheel and 35 the drive shaft, connections for driving the extension shaft from the turn table, connections between the extension shaft and the other of the screw shafts enabling the driving of the screw shafts in unison, shift- 40 able clutch connections between the extension shaft and the companion screw shaft, a tone arm having a reproducer, a tone arm carriage actuated by one of the screw shafts, and a friction wheel carriage actuated by 45 the other of the screw shafts, said carriages being arranged to convey the reproducer and the friction wheel toward the center of the turn table together.
6. In a phonograph, a tone arm carriage, 50 means for supporting and guiding the carriage, a sound conduit attached to the tone arm carriage, a screw follower plate hinged to the tone arm carriage, a screw follower mounted on the plate, a tone arm including 55 a tubular portion mounted on the hinged plate and having a loose telescopic connection with the sound conduit to enable the raising of the hinge plate and the screw follower, and a screw shaft for actuating 60 the screw follower and the tone arm carriage.
7. In a phonograph, a yoke carried by a driven shaft, a drive shaft carried by the yoke and operated by the driven shaft, a
- friction wheel slidably keyed on the drive shaft, and a drive screw shaft with means for sliding the friction wheel on the drive shaft as it is driven thereby.
8. In a phonograph, a driven spindle, a turntable, a driven friction wheel in contact with the turntable, a screw shaft with means for controlling the advance of the friction wheel, a screw shaft for controlling the advance of a tone arm in unison with the friction wheel, and means providing a common driving connection for both screw shafts from the spindle.
9. A phonograph, comprising a main driving element, a spindle with a turntable, a friction wheel in contact with the turntable, with means by which it is driven from the main driving element; a screw shaft, with means by which the friction wheel is advanced; a tone arm, with a screw shaft by which it is advanced in unison with the friction wheel; and connecting means for driving the screw shafts from the spindle and at a variable speed in accordance with that imparted to the turntable by the friction wheel.
10. In a phonograph, a turntable, a friction wheel by which the turntable is driven, a screw shaft by which the advance of the friction wheel is controlled, a pivoted connection between the screw shaft and friction wheel, and means carrying the friction wheel, tiltably mounted to simultaneously disconnect the friction wheel from the turntable and the connecting means from the screw shaft, and vice versa.
11. In a phonograph, a yoke pivoted on a driven shaft, a drive shaft journaled in the yoke, with driving connections to the driven shaft, carrying a friction wheel in contact beneath a turntable; a screw shaft driven from the spindle of the turntable, a pivotally and slidably mounted follower in connection with the friction wheel, and means for tilting the yoke to simultaneously engage the friction wheel with the turntable and the follower with the screw shaft, and vice versa.
12. The combination in a phonograph, of a feed screw for moving a wheel in respect to a turntable, and means for concomitantly removing the wheel from driving engagement with the turn table and driven engagement from the feed screw.
13. The combination in a phonograph, of a feed screw, a wheel for moving a turn table, a connection between the feed screw and wheel for moving the friction wheel radially in respect to the turn table, and means for displacing both the friction wheel and connection in one movement and vice versa.
14. In a phonograph, a friction wheel which engages with and is advanced in respect to a turn table, and means by which the

wheel is supported, including a resilient arm by which the friction of the wheel against the turn table is maintained.

15. In a phonograph, a friction wheel, a wheel-supporting yoke which is tiltable to engage the wheel with a turntable, a feed screw, and a follower in operative connection

with a part of the wheel, also tiltable with the yoke to engage the feed screw when the wheel engages said turntable.
